ELECTRICAL SIGNALING SYSTEM

Leon Joly and Louis Charles Andres, Paris, France, assignors to International Standard Electric Corporation, New York, N. Y., a corporation of Delaware

Application March 10, 1943, Serial No. 478,700
In France May 28, 1941

7 Claims. (Cl. 179—2)

1

The present invention refers to signaling systems and particularly to signaling systems for the remote transmission of codes capable of being used for purposes of remote metering, remote control, remote indication, and the like, by means of an ordinary telephone line which can also be used for the transmission of telephone calls and messages.

One object of the invention is to provide a code signaling system of this type in which the codes consist of direct currents of differential intensities and polarities, and are decoded at the receiving station by means of suitably arranged and designed decoding relays.

Another object of the invention is to provide means at each receiving station to send back to the transmitting station an acknowledge signal at the end of the transmission of each code, each transmitting station having means for receiving, decoding and registering the acknowledge signal.

Still another object of the invention is to branch a telephone speaking circuit, and if desired also a ringing circuit to the line, preferably in such a manner that the decoding relays are not influenced by any speaking or ringing currents transmitted.

These and other objects are accomplished, according to the present invention, by the arrangement and combination of elements set forth in the following description, defined in the appended claims and illustratively exemplified in the accompanying drawings, in which

Fig. 1 is a wiring diagram of one station of a signaling system according to the invention;

Fig. 1A illustrates a modification of the system according to Fig. 1;

Fig. 2 is a wiring diagram of one station in a system including automatic means at each station for sending back an acknowledge signal and also means for receiving and registering such acknowledge signal.

Fig. 3 is a diagram of a telephone circuit to be used in the signalling system according to Fig. 1 if the calling is effected by code;

Fig. 3A illustrates a modification of the telephone circuit according to Fig. 3; and

Fig. 4 is a wiring diagram of a similar telephone circuit including means to effect ringing with an alternating current.

The equipment of only one of the two con-

nected stations is shown in each of the various figures, because the equipments of the two stations connected by the line L are absolutely identical, and the description of the structure and operation of one station is applicable to the structure and operation of the other station.

In the various figures, the same reference characters are applied to corresponding elements.

Referring first to Fig. 1, the station circuit shown comprises four decoding relays, A, B, C, D. Relays A and B are connected in a decoding circuit loop to one of the wires of line L and relays C and D to the other wire over contacts 1 and 3 of a reversing switch I₁ in the normal, receiving, position of the latter. The decoding relays are polarized, either by their design or, as shown in Fig. 1, by the connection in parallel to their windings of unidirectional conductors R, such as dry rectifiers, or else as shown in the alternative of Fig. 1A, by the placing in series with their windings of unidirectional conductors R. Two relays A and C are arranged to operate when a current of certain value passes through their windings and the remaining relays B and D, when a current of a different value, e. g., of higher value passes through them.

The four code signals used are indicated in the drawing by the graphical representation bracketed under wires a and b, which are connected to the normally open contacts 2 and 4 of the reversing switch I₁. The four codes consist of currents of different polarities and of different strengths. For this purpose, code-sending wires a and b may be connected to a battery by means of a code selecting switch (not shown) whereby the battery can be connected, either with one polarity or with an inverse polarity, to the wires of line L over contacts 2 and 4 of the reversing switch I₁, in addition to which resistances may or may not be inserted between the battery and wires a and b according to the positions of the code selecting switch.

When the code selecting switch has closed a circuit a, b in one of its operating positions, for example to the positive battery for wire a and to the negative for wire b without the insertion of any resistances (code 3), and reversing switch I₁ has closed contacts 2 and 4, disconnecting at the same time relays A, B, C, D at the transmitting station from line L, the battery loop is closed

2

over line L and contacts 1 and 3 of the receiving station to the four relays A, B, C, D of the receiving station. One of these relays (for instance D), which is sensitive to the strength and the direction of the current thus transmitted, operates and, through its contact, records the code transmitted. It is evident that in this example, as in the following ones, the four unit figure adopted for the codes is given only as an illustration and that as many codes may be provided as desired by inserting a corresponding number of resistances of different values between the battery and wires a, b through the code-selecting switch. At the same time as the operation of relay D, relay C will also operate, so that the code is here represented by the simultaneous operation of relays C and D, in distinction from the code represented by the operation of relay C alone.

In order to have assurance at the sending station that the code signal transmitted has been recorded correctly, means may be provided at the receiving station to send back to the sending station an acknowledge signal at the end of each code transmitted. An example of a station circuit incorporating such means is shown in Fig. 2.

One of the decoding relays, e. g., relay D, is assigned exclusively to the control of the code reception and its front contact is connected to an audible or visible indicating device or electric locking device E, which may have an energizing circuit controlled by a normally open contact 5 of the reversing switch I₁. When relay D closes, positive battery is applied to indicating device E. Indicator E may respond thereto in any suitable manner, as well known in the art, such as by ringing a bell, showing a light or other visible signal, or displaying any type of temporary signal which may be distinguishable. Indicating device E may alternatively be energized by positive battery being applied thereto through the closure of switch 5 when the station is thrown into the transmitting position, as described in the following paragraph.

When the reversing switch I₁ is operated at the sending station, the indicating or recording device E operates at this same station through the closing of contact 5, to produce an indication as soon as a current is sent over line L through contacts 2 and 4. At the receiving station, one of the relays A, B or C is energized, depending upon the code transmitted.

Incoming signals pass through the windings of relays A, B, C and D in series and cause selective energization thereof, as already explained in connection with the description of Fig. 1. Relays A and B have back contacts in series with positive battery and the windings of relays A' and B'. When a signal having an intensity below the marginal response value of relay B is received, relay A will take battery through the closed contacts of relay B, and by the closure of its own contacts will apply battery to relay A'. A signal having intensity sufficient additionally to actuate relay B, will open the circuit through the contacts of relay A and additionally will apply battery directly to relay B'. Thus, only one relay will effectively respond to a given code signal. Relay C, when actuated, applies battery directly to relay C'. The operation of relay D, which is non-polarized and non-marginal, has already been described; this relay always actuating indicator E, irrespective of the type of code signal being received. The operation of the other set of contacts on each of relays A, B and C, so as to apply current to relay D, whenever a decoding

and corresponding auxiliary relay are operated, is thought to be fully evident from the circuit shown in Fig. 2.

In the arrangement shown in Fig. 2, each of the normal decoding relays A to C is associated with a relay A' to C' each having one terminal thereof connected through a front contact of the corresponding A to C relay to one of the terminals of a battery, while the other terminal of each relay A' to C' is connected to the other terminal of the battery. As a result, one of the relays A', B' or C' operates at the receiving station, depending upon which one of the relays A, B or C has been energized by the code transmitted. The front contacts of relays A', B' and C' are connected in parallel to the winding of a relay D' which is thus always energized regardless of which one of the relays A, B or C is operated. At its front contact, relay D' prepares the energizing circuit of an acknowledge relay D'' having back contacts which are normally inserted in the wires of line L.

Relay D' is a slow release relay. Consequently, when the reversing switch I₁ is returned to normal position at the sending station, that one of relays A, B and C that had operated at the receiving station releases and at its back contact momentarily closes the energizing circuit of the acknowledge relay D'' across the front contact of relay D' which remains temporarily closed. Relay D'' at its front contacts connects to the line over wires e and f a battery of definite polarity and voltage values to transmit an acknowledge code. The acknowledge code operates at the sending station the control relay D. In operating, relay D controls at its front contact an operation of the recording or indicating device E which serves, e. g., to cancel in the device E the indication produced by its energizing circuit and to produce an acknowledging recording of the code transmitted to the receiving station.

As soon as relay D' of the receiving station releases, it causes the release of relay D'' of the receiving station and relay D of the sending station. The circuits are then available for a new code transmission.

In addition to the code transmission circuits, a telephone speaking circuit AT₁ may be branched to the line L, as shown in the diagram of Fig. 3, in parallel with the decoding relay circuit at contacts 1 and 3 of the reversing switch I₁. In this way, a telephone conversation can take place when the reversing switch I₁ is in its normal position, after a ringing signal has been transmitted, e. g., by means of one of the signaling codes assigned to that function. Wires c and d of the telephone circuit are connected to contacts 1 and 3 of the reversing switch I₁ through condensers T in order to avoid the introduction of direct signaling current into the telephone circuit.

The telephone circuit may be connected either directly in loop, as shown at AT₁ in Fig. 3, or preferably with ground return, as shown at AT₂ in Fig. 3A. In this latter case, telephone conversation is always possible even if one of the wires of line L should be broken.

Instead of using code ringing, as in the case of the circuit of Fig. 3, it may be preferable to do the telephone ringing by means of alternating current, and for this purpose one embodiment of the invention provides a second reversing switch I₂ (Fig. 4), having back contacts 6, 7 which are inserted in series with back contacts 1, 3 of the reversing switch I₁ in the wires running

in parallel to the telephone circuit and to the decoding circuit. The front contacts 8, 9 of the reversing switch I₂ are connected in parallel to one terminal of a telephone ringing current generator G of any suitable type.

The reversing switch I₂ may consist either of a key connecting the ringing current source G to the line L or of a relay actuated by a cam contact of a hand generator G.

The call is received at the called station by a bell or a lamp panel S that is normally placed in circuit with ground return by the back contact of a cradle switch K. The cradle switch K, in its normal position, isolates the telephone equipment AT from the line and, in its operating position, connects the telephone equipment AT to the line while opening the circuit of the call receiving device S.

In this way, the telephone speaking circuit is rendered independent of the code signaling circuit, at least while this latter remains in normal position, i. e., while reversing switch I₁ is not operated. The code relays are not traversed by any current during the transmission of the telephone ringing or speaking current because the two line wires remain at the same electric potential. Further, since the return of the telephone circuit is provided by the ground, telephone conversation and ringing always remain possible, even if one of the wires of line L should be broken.

The circuits described may be modified in numerous ways within the scope of the following claims.

We claim:

1. A signaling system for the transmission of electric code signals between two identical stations connected by a two conductor line, each of said stations comprising signal transmitting equipment including two output wires, and means to supply to said output wires various direct currents corresponding, respectively, to the signal codes to be transmitted, each of said currents having a characteristic intensity and a characteristic flow direction, signal receiving equipment including two input wires, a decoding circuit connected to said input wires and containing for each signal code which may be received a normal decoding relay being designed and arranged in said decoding circuit to respond only to current of an intensity and flow direction corresponding to that of the associated signal code, a reversible switch to connect said line conductors normally to said input wires and optionally to said output wires, and control equipment including means to supply to said line conductors a control code of a characteristic current intensity and flow direction, a control relay responsive to said control code in said decoding circuit, an indicator controlled by a front contact of said control relay, a slow release relay, a circuit passing current through said slow release relay upon exclusive energization of any one of said normal decoding relays, an acknowledge relay, an energizing circuit for said acknowledge relay containing in series a front contact of said slow release relay and back contacts of all said normal decoding relays, and means controlled by said acknowledge relay to connect the line conductors to said control code supply means while disconnecting them from said input wires of the receiving equipment.

2. A signaling system, as claimed in claim 1, including for each normal decoding relay an aux-

iliary relay, each auxiliary relay being adapted to be energized over a front contact of the corresponding normal decoding relay, said circuit for passing current through said slow release relay comprising for each of said normal decoding relays a parallel branch, each of said branches containing a front contact of one of said auxiliary relays, whereby the flow of current through the contacts of said normal decoding and said auxiliary relays effectively distinguishes between two code signals having the same polarity but having different intensities so that only a single one of said auxiliary relays will respond to a pre-determined code signal and actuate said slow release relay.

3. A signaling system, as claimed in claim 1, including an energizing circuit for said indicator, a contact in said indicator energizing circuit controlled by said reversible switch to energize the indicator and to produce an indication when said switch is operated to connect the line conductors to said output wires, the front contact of said control relay operating said indicator to cancel such indication.

4. A signaling system for the transmission of electric code signals and the exchange of telephone messages between two identical stations connected by a two-conductor line, each of said stations comprising signal transmitting equipment including two output wires, and means to supply to said output wires various direct currents corresponding, respectively, to the codes to be transmitted, each of said currents having a characteristic intensity and a characteristic current flow direction, signal receiving equipment including two input wires, a decoding circuit connected to said input wires and containing for each code which may be received a decoding relay, each decoding relay being designed and arranged in said decoding circuit to respond only to a current of an intensity and flow direction corresponding to that of the associated code, a reversible switch to connect said line conductors normally to said input wires and optionally to said output wires, and telephone circuits including telephone equipment and two branch conductors for said equipment each containing a condenser, said branch conductors being connected in parallel to the input wires of said receiving equipment.

5. A signaling system, as claimed in claim 4, in which said telephone equipment is connected serially in a loop across said branch conductors.

6. A signaling system, as claimed in claim 4, in which both said branch conductors are connected in parallel to one terminal of said telephone equipment, the other terminal of which is grounded.

7. A signaling system, as claimed in claim 4, in which each station includes a generator for alternating ringing current, one terminal of said generator being connected to ground, a second reversible switch for disconnecting said branch conductors from said line conductors while connecting both of the latter in parallel to the other terminal of said generator, a cradle switch connected in parallel to both said branch conductors, and an indicator responsive to ringing current, said indicator having one of its terminals grounded and its other terminal connected to both said branch conductors over said cradle switch in one position thereof, said telephone equipment having one of its terminals grounded and its other terminal connected to both said

branch conductors over said cradle switch in the second position of the latter.
